TRUMAN BRISTOL, OF CHESHIRE, ASSIGNOR TO HIMSELF AND CHARLES MONSON, OF NEW HAVEN, CONNECTICUT.

Letters Patent No. 102,909, dated May 10, 1870.

IMPROVEMENT IN WATER-WHEELS.

The Schedule referred to in these Letters Patent and making part of the same.

To all whom it may concern:

Be it known that I, TRUMAN BRISTOL, of Cheshire, in the county of New Haven and State of Connecticut, have invented a new Improvement in Water-Wheels; and I do hereby declare the following, when taken in connection with the accompanying drawings, and the letters of reference marked thereon, to be a full, clear, and exact description of the same, and which said drawings constitute part of this specification, and represent in—

Figure 1 a front view, looking from the wheel-pit;
Figure 2, a top view;

Figure 3, a section on line $z z$; and in

Figure 4, a section of the wheel on line $z z$.

This invention relates to an improvement in water-wheels, the object being to reverse the action of the wheel whenever occasion requires, and dispense with the extensive and complicated machinery heretofore used for reverse motion.

The uses to which such wheels may be applied are numerous, but I design this for raising and lowering, as for mining and similar purposes; and

The invention consists in the construction of the wheel with two sets of buckets, either one of which may be used at pleasure, the water acting upon one set of buckets to turn the wheel in one direction, and upon the other set to reverse the revolution of the wheel, whereby, changing the influx of water from one set to another, the power may be reversed.

I represent my invention as applied to an overshot-wheel, as the most convenient mode of illustration, yet the inventor designs the same as also applicable to water-wheels of other forms.

a are one set of buckets;

b, a second set on the same shaft, and this set here represented of equal capacity.

Over the wheel is arranged the water-way *A*, and two openings *c d*, and over these openings an oscillating gate, *B*, so as to close either one of the said two openings, or both, yet, so that but one of the openings can be opened at the same time.

From the pivot of the gate a lever, *C*, extends to a convenient position for operating the gate.

As represented in fig. 2, the gate is turned to uncover the opening *d*, which admits water into the buckets *B*, turning the wheel into the direction denoted by the arrow in fig. 4.

Now, if the gate be turned, as denoted by broken lines, fig. 2, to close the opening *d*, and uncover the opening *c*, then water will be admitted onto the buckets *a* to cause the wheel to revolve in the reverse direction, as denoted by the arrow in fig. 3. Thus, as often as the reverse movement is required, it is only necessary to cut off the water from one wheel, admit it to the other; or, to stop the power and turn the gate to close both openings.

In raising water, this automatic change is preferred, but in hoisting rocks, minerals, &c., from mines, the kettle has to remain an uncertain time in the shaft to be filled, and an automatic action in changing the direction of the power is impracticable. The said changing must then be at the will of an operator, and may be effected by the miner in the shaft, or elsewhere, by the pulling of a rope, and thus moving or reversing the wheel. During the said uncertain time, both the wheel water-ports may be closed, and the water escape elsewhere, or the windlass may be temporarily detached from the water-wheel.

As a convenient means for automatically operating the gate, for mining and like purposes, I arrange a double run of rope *D E*, coiled around a drum, *F*, on the wheel-shaft, so that the wheel revolving in one direction winds one run and unwinds the other, and *vice versa*.

I arrange a lever, *G*, upon a pivot, *g*, with a sheave, *h* for one run, and a similar sheave, *i*, for the other run, and also a loose sheave, *n*, for one run, and a similar loose sheave, *m*, for the other run, the loose sheaves *n* and *m* pivoted respectively to the lever *G* at *s* and *t*.

The wheel running, so as to draw in the run *D*, which passes freely through the lever, the sheave *n* swinging out, and so runs until an enlargement, *R*, on the other run *E*, strikes the loose sheave, and clamps the rope with sufficient force to turn the lever to the position in fig. 3.

The said lever *G* is attached to the gate-lever *C* by a connection, *H*, (see fig. 2,) so that when the lever *G* is turned, as described, it turns the gate, and admits water onto the other set of buckets; then the run *E* is drawn in, and the run *D* out, until the sheave *n* is, by an enlargement, or other device on the rope, operated, as before described, to stop the run; then the lever will be turned, as denoted by broken lines, fig. 3, and close the gate on one side, and open the reverse side, and so continue to do, being governed in its operation by the enlargements or stops on the ropes. Other devices may be employed for changing the motion.

I claim as my invention—

In a water-wheel, the arrangement of two independent sets of buckets, combined with a device for conducting water to the two sets, and so that the flow of water may be changed from one set to the other to reverse the revolution of the wheel, substantially as described.

TRUMAN BRISTOL.
